Barkume LLP(57) **CLAIM**

The ornamental design for an oval lightcap for robotic arm as shown and described.

DESCRIPTION

FIG. 1 is a perspective view of an oval lightcap for robotic arm showing our new design;

FIG. 2 is a front view of the article of FIG. 1;

FIG. 3 is a bottom view of the article of FIG. 1;

FIG. 4 is a left view of the article of FIG. 1;

FIG. 5 is a right view of the article of FIG. 1;

FIG. 6 is a top view of the article of FIG. 1;

FIG. 7 is a perspective view of the article of FIG. 1 within a portion of a robotic arm; and,

FIG. 8 is a back view of the article of FIG. 1.

The portions of a robotic arm, shown in overexposed view in FIG. 7, are for the purpose of illustrating environment that forms no part of the claimed design.
